CLAIM

The ornamental design for a merchandizing display stand, as shown and described.

DESCRIPTION

FIG. 1 is a perspective view of a merchandizing display stand showing our new design;

FIG. 2 is an end elevational view, the opposite end being a mirror image thereof;

FIG. 3 is a top plan view;

FIG. 4 is a side elevational view, the opposite side being a mirror image thereof; and

FIG. 5 is a bottom plan view thereof.

FIGS. 2-5 have been shown on a reduced scale with respect to FIG. 1.

FIG. 1

FIG. 2

FIG. 3

FIG. 4

FIG. 5
